UNITED STATES PATENT OFFICE.

JULIUS GERSON, OF NEW YORK, N. Y.

DESIGN FOR AN AUTOGRAPH-SHEET.

SPECIFICATION forming part of Design No. 13,696, dated March 6, 1883.

Application filed February 5, 1883. Term of patent 7 years.

To all whom it may concern:

Be it known that I, JULIUS GERSON, of the city, county, and State of New York, have invented a new and original Design for Autograph-Sheets, of which the following is a full, clear, and exact description.

This invention has reference to an improved design for a collective autograph - sheet to be used at dinner-parties, on birthdays, and for lodge, club, school, and other festivities; and the design consists of an autograph-sheet composed of a series of irregularly-grouped representations of visiting-cards, which are inclosed by an ornamental border or frame.

15 The nature of my design is fully shown in the accompanying drawing, to which reference is made.

20 A A represent a number of representations of visiting-cards, which are irregularly grouped together and inclosed by a surrounding ornamental frame or border, B. The visiting-cards are so arranged that each presents a space large enough for an autograph signature. Back of the visiting-cards A A appears the 25 background of the panel, inclosed by the ornamental frame B, the design forming an imita-

tion of a mirror or picture frame in which the visiting-cards have been irregularly stuck, so as to be thus supported by the frame and by each other.

Having thus described my invention, I claim as new and desire to secure by Letters Patent—

30 1. The design for an autograph-sheet, composed of irregularly-grouped representations of visiting-cards and of an ornamental surrounding frame or border, substantially as shown and described.

35 2. The design for an autograph-sheet, composed of irregularly-grouped representations of visiting-cards and of an ornamental surrounding frame or border, said cards being supported by the frame and by each other or the panel of the frame, substantially as shown and described.

40 In testimony that I claim the foregoing as my invention I have signed it this 31st day of January, 1883.

JULIUS GERSON.
